NARROWING DEVICE FOR FLAT KNITTING MACHINES

Georg Richter, Chemnitz, Germany

Application May 31, 1941, Serial No. 396,135
In Germany May 30, 1940

4 Claims. (Cl. 66—89)

(Granted under the provisions of sec. 14, act of
March 2, 1927; 357 O. G. 5)

The present invention relates to a narrowing device for flat knitting machines of the Cotton type and more particularly is concerned with a flat knitting machine having a jacquard attachment.

One of the known narrowing devices, serving control purposes, has a great drawback in so far as at higher speeds the narrowing rollers, due to the required displacements, are subjected to the largest vibrations, so that owing to inexact adjustments narrowing defects or even the danger of breakage is liable to occur.

In accordance with the present invention this drawback is removed by holding, with the aid of a safety or locking device, a narrowing roller, scanning the narrowing cams, in any selected position against lateral displacement. The safety or locking device consists of a lever provided with a bolt and connected to the roller shifting fork, and bell crank levers mounted in the range of this lever which are arranged one above the other and have stepped recesses. These bell crank levers are kinematically connected to said lever. On adjustment of the roller shifting fork, simultaneously the lever and therewith the bolt as well as the bell crank levers are adjusted in such a manner that the stepped recesses surround the bolt in any selected position and thereby lock the narrowing rollers in the selected position. Connected to the bell crank levers are tension springs the other ends of which are fixed to the machine frame. These springs withdraw the bell crank levers into their starting position after locking has been effected.

In the accompanying drawings one construction according to the present invention is shown by way of example.

In these drawings:

Fig. 1 is a front elevation of portion of a safety or locking device according to the invention.

Fig. 2 is the plan view of the device shown in Fig. 1 in an enlarged illustration.

Fig. 3 is a side elevation of the device shown in Fig. 1 also in an enlarged illustration.

Fig. 4 is a view showing the narrowing rollers in the position for blind narrowing.

Fig. 5 is a view showing the position of the narrowing rollers for a one needle rack towards the right.

Fig. 6 is a view showing the position of the narrowing rollers for a one needle rack towards the left.

Fig. 7 is a view showing the position of the narrowing rollers for a two needle rack towards the right, and

Fig. 8 is a view showing the position of the narrowing rollers for a two needle rack towards the left.

In agreement with the twofold divided narrowing device, the arrangement is present in duplicate, as may be seen from the drawings.

To explain the arrangement only the device of the one portion is described, as this device in the second portion is identical with that of the first portion.

Mounted upon the cam shaft 1 are narrowing cams 2, 3, 4, 5 and 6 which, in a well known manner, may be scanned by narrowing rollers 7 and 8. The narrowing roller 7 is rigidly fixed upon a bolt 9 of a lever 10, whereas the narrowing roller 8 may be displaced upon the bolt 9 by means of a roller shifting fork 11. The lever 10 transmits the movements of the cams upon a stepped wedge not shown in the drawings which in turn displaces the narrowing points also not shown in the drawings.

The roller shifting fork 11 is fixed upon a bolt 12 which in turn carries a link member 13 mounted upon a vertical shaft 14. The latter is pivotally arranged in the machine frame and carries a lever 15 which may be influenced in the direction of the arrow x shown in Fig. 2 by means of a connecting rod 16. The latter cooperates with a lever 18 pivoted upon a vertical shaft 17. Fixed to the lever 18 is a bolt 19.

Upon another vertical shaft 20, mounted in the machine frame, bell crank levers 21, 22, 23, 24, 25, 26 and 27, 28 are pivotally arranged one above the other. The longer lever arms 21, 23, 25, 27 of these bell crank levers are provided with stepped recesses 29, 30, 31, 32 respectively which may be swung into the range of the bolt 19, whereas the short lever arms 22, 24, 26, 28 are connected by means of springs 33, 34, 35, 36 respectively to connecting rods 37, 38, 39, 40 respectively which may be influenced in the direction of the arrow y shown in Fig. 2. The lever arms 21, 23, 25, 27 are actuated by springs 41 fixed to the machine frame. The rod 16 as well as the rods 37, 38, 39 and 40 are kinematically connected and may be influenced by a jacquard device.

As has already been mentioned, the described arrangement is present in duplicate in accordance with the twofold divided narrowing device. The arrangement, of course, may be correspondingly altered in case of another division of the narrowing device.

The operation of the device is as follows:

By operating in the directions of the arrows

the connecting rod 16 and the connecting rods 31, 38, 39, 40 kinematically connected thereto, the shaft 14 on the one hand is turned by way of the lever 15 and therewith an adjustment of the roller shifting fork 11, by way of the link member 13, is effected which fork 11 adjusts its narrowing roller 8 to the corresponding cam and transmits the scanned cam movements upon the lever 10 and, therefore, upon the narrowing device. On the other hand, the corresponding bell crank lever is turned in such a manner that its recess surrounds the bolt 19 and thereby locks the connecting rod 16, the lever 15, the shaft 14, the link-member 13 and the roller shifting fork 11 with its narrowing roller 8 in the selected position.

In Fig. 2 the bell crank lever 21, 22 has been operated, whereby the narrowing roller 8 has been brought into the range of the cam 4 by means of the connecting rod 16. The recess 29 of this bell crank lever surrounds the bolt 19 of the lever 18 and thereby locks the position of the narrowing roller 8.

After the narrowing operation has been effected during which the connecting rods are released, the bell crank lever returns into its position of a rest by the action of its tension spring 41 and a new narrowing position may be adjusted.

Due to locking the roller rack positions a narrowing operation free of objection is ensured even with the highest speeds.

From Figs. 4 to 8 it may be seen that the narrowing roller 7 always occupies a position in the path of the narrowing cam 2, whereas the narrowing roller 8 may be brought into the path of the cams 3, 4, 5, 6 or may be moved totally out of their path according to the rack to be effected.

What I claim is:

1. A narrowing device for flat knitting machines of the cotton type provided with a

jacquard attachment, comprising narrowing cams, narrowing rollers scanning said cams, one of said rollers being rigidly fixed upon a bolt of a lever and the other of said rollers being displaceably arranged upon said bolt of said lever, and a locking device for automatically locking against lateral movement said displaceable narrowing roller in any selected position.

2. A narrowing device for flat knitting machines of the cotton type provided with a jacquard attachment, comprising narrowing cams, narrowing rollers scanning said cams, one of said rollers being rigidly fixed upon a bolt of a lever and the other of said rollers being displaceably arranged upon said bolt of said lever, and a locking device for automatically locking against lateral movement said displaceable narrowing roller in any selected position, said locking device consisting of a lever connected to a fork, adapted to shift said movably arranged narrowing roller, and provided with a bolt, and of bell crank levers mounted one above the other in the range of said lever and provided with stepped recesses, said bell crank levers being kinematically connected to said lever.

3. A narrowing device as set forth in claim 2 in which with an adjustment of said roller shifting fork simultaneously said lever and therewith said bolt as well as said bell crank levers are shifted in such a manner that said stepped recesses surround said bolt in any selected position and therewith lock said narrowing rollers in position.

4. A narrowing device as set forth in claim 2 in which tension springs, fixed to the machine frame, are connected to said bell crank levers, said springs being adapted to withdraw said bell crank levers into their starting position after locking has been effected.

GEORG RICHTER.
